UNITED STATES PATENT OFFICE.

ALEXANDER YESSAIAN, OF CHELSEA, MASSACHUSETTS, ASSIGNOR OF ONE-HALF TO
STEPHEN DEVRIGIAN, OF CHELSEA, MASSACHUSETTS.

CIGARETTE HOLDER.

Application filed March 21, 1927. Serial No. 177,161.

This invention relates to devices for holding cigarettes or cigars while smoking the same and while lighted incident to smoking, and for purposes of explanation, reference will be made hereinafter only to cigarettes holding, keeping in mind however that the device may be constructed also for holding cigars.

It is one object of the invention to provide a new and improved cigarette holder embodying a ring to be worn on one of the user's fingers, and a shank projecting from the ring and carrying cigarette-holding jaws and actuating means therefor, said shank spacing the cigarette a safe distance from the hand to prevent accidental burning.

Further objects of the invention are to provide novel actuating means for the jaws connected in a unique manner therewith and to make novel provision permitting easy assembly of parts.

With the foregoing in view, the invention relates to the novel subject matter herein-after described and claimed, the description being supplemented by the accompanying drawing.

Fig. 1 is a side elevation of a cigarette holder constructed in accordance with my invention.

Fig. 2 is a longitudinal sectional view on line 2—2 of Fig. 1.

Fig. 3 is a longitudinal section on line 3—3 of Fig. 2.

Fig. 4 is a horizontal or transverse sectional view on line 4—4 of Fig. 1.

Fig. 5 is an additional horizontal section on line 5—5 of Fig. 1.

Fig. 6 is a perspective view of the main and auxiliary parts of the shank in juxtaposition.

Fig. 7 is a perspective view of the jaws and actuating parts therefor, separated from each other.

In the drawings above briefly described, the preferred form of construction has been illustrated, and while such construction will be hereinafter specifically described, it is to be understood that within the scope of the invention as claimed, variations may be made.

The numeral 8 designates a ring to be worn preferably on the forefinger, and 9 denotes a tubular shank rigidly joined to and projecting radially from said ring. The major portion of the shank 9 is preferably of circular cross section, but the particular shank herein disclosed, is of square cross section at its upper end portion, and the upper extremity of this shank is formed with a notch or recess 10 which opens through opposite sides of the shank as well as through said extremity, the opposed side walls 11 of the recess 10, being preferably given a substantially three-quarter circular shape at their upper ends, providing ears 12. A pair of cigarette-holding jaws 13 have overlapping hinge knuckles 14 which are interposed between the ears 12, and a pivot pin 15 is passed through said knuckles and ears, said pin mounting the jaws 13 in such position that portions of the latter project laterally beyond the opposite open ends of the recess 10. These recess ends are closed by plates 16 which contact slidably with the exterior of the shank 9, said plates being pivotally connected with the laterally extending portions of the jaws 13. This is preferably accomplished, by providing the plates with laterally turned upper ends 17 which engage the lateral portions of the jaws 13 and are formed with openings 18, said lateral portions of the jaws being provided with curved hooks 19 which are received in said openings.

A jaw-actuating rod 20 is disposed within the shank 9 and is provided at its upper end with a head 21 received in the recess 10, the opposite ends of said head being rigidly joined to the plates 16, in any desired manner. The shank has been shown as provided with an internal shoulder 22 around the rod 20, and a coiled compression spring 23, within said shank, has been illustrated between said shoulder and the head 21. Thus, the upward pressure of the spring, causes movement of the jaws 13 toward each other, but when the rod 20 is pulled downwardly, opening of said jaws is effected, either for the purpose of inserting a cigarette or for discharging a butt. For so slid-

ing the rod 20, I provide its lower end with a laterally projecting finger-piece 24 which extends to the exterior of the shank 9 through a slot 25, said finger-piece being sufficiently close to the ring 8, to permit it to be readily pulled down by the user's thumb.

At 26, a longitudinal portion of the shank 9 is cut away providing an elongated recess.

- 10 The upper end wall 27 of this recess is undercut and is provided with a downwardly projecting lug 28. The lower end wall 27^a of the recess 26 is preferably at right angles to the axis of the shank 9 and is formed 15 with an upwardly projecting lug 28^a. A transversely curved plate 29 fills the recess 26 and is shaped to contact tightly with all walls or edges of this recess, upper and lower notches 30 and 30^a being formed in said 20 plate to receive the lugs 28 and 28^a. The lower end of plate 29 is provided with an ear 31 which extends into the interior of the shank 9, and a pin 32 passes through said ear and through opposite sides of the shank. 25 Thus, the plate 29 is effectively secured in place and is held against movement in all directions, yet if necessary, said plate may be removed to gain access to the inner end or hub portion 33 of the finger-piece 24. 30 The construction just described however, is intended primarily to permit easy assemblage of parts, and it will be observed that the slot 25 through which the finger-piece 24 projects, is formed in the plate 29.

35 To assemble the device, the rod 20 is inserted into the upper end of the shank 9 and the hub portion 33 of the finger-piece 24 is positioned in the upper end of the recess 26.

- 40 The proportion of parts is such that the rod 20 may now be rotated to thread its lower end into the hub 33, while the plates 16 are above and cannot strike the ears 12. When the rod and the finger-piece have been thus connected, the hooks 19 of the jaws 13 may 45 be engaged with the openings 18. Then, the knuckles 14 are aligned with each other and positioned between the ears 12, being held by the pin 15 which is now inserted. The upper end of the plate 29 may now be engaged with the undercut end wall 27 of the recess 26 and said plate rocked into operative position to fill said recess, the finger-piece 24 being passed outwardly through the slot 25. Now, upon insertion of the pin 32, 55 all parts are quickly assembled and held against possible accidental disconnection from each other. Yet, if repairs should be necessary, the parts of the device may be readily disconnected by a skilled workman.

- 60 The device may be obviously used to advantage, while the hand upon which it is worn, is free for use in other capacities than merely holding the cigarette. Moreover, if the device is taken from the finger and laid down with a burning cigarette held by the

jaws 13, the burning end of said cigarette will not contact with the surface upon which the cigarette and holder have been laid, due to the fact that the jaws 13 are disposed in a plane at an angle to the plane in which the ring 8 is positioned. This relation of ring and jaws also permits the cigarette to be placed in the mouth without moving the hand to an awkward position.

I claim:—

1. A cigarette holder comprising a tubular shank, a pair of jaws pivoted to one end thereof, a finger ring secured to the other end of said shank, a rod within the shank having pivotal connection with both jaws, a spring within the shank acting on said rod to normally close the jaws, and a thumb piece projecting laterally from the rod near said ring, the shank being formed with a slot through which said finger-piece passes.

2. In a cigarette holder, a tubular shank having a transverse recess in one end which opens through opposite sides of said shank and communicates with the interior of said shank, a pair of jaws pivoted at their inner ends to the recessed end of the shank, said jaws having portions projecting outwardly from said opposite sides of the shank, two plates slidably contacting with said opposite sides of the shank and closing the ends of the recess thereat, means pivotally connecting said plates to said outwardly projecting portions of the jaws, and a jaw-actuating rod in the shank having a head in the aforesaid recess connected to said plates, inward movement of said rod serving to open the jaws.

3. In a cigarette holder, a tubular shank having a transverse recess in one end which opens through opposite sides of said shank and communicates with the interior of said shank, a pair of jaws pivoted at their inner ends to the recessed end of the shank, said jaws having portions projecting outwardly from said opposite sides of the shank, two plates slidably contacting with said opposite sides of the shank and closing the ends of the recess thereat, said plates having laterally projecting end portions contacting with said outwardly projecting jaw portions and formed with openings, hooks on said jaw portions passing through said openings and pivotally connecting the jaws and plates, and a jaw-actuating rod in the shank having a head in the aforesaid recess connected to said plates, inward movement of said rod serving to open the jaws.

4. In a cigarette holder, a tubular jaw-carrying shank having a longitudinal portion of one of its sides cut away, providing an elongated recess, one end wall of said recess being undercut and formed with a lug projecting toward the other end wall, a jaw-actuating rod within the shank, a finger-piece on said rod projecting laterally

therefrom at said recess, a transversely curved plate filling said recess and shaped to tightly contact with the walls thereof, said plate being formed with a notch snugly receiving 5 the aforesaid lug and also having a slot through which said finger-piece passes, an inwardly extending ear on the end of the

plate remote from said notch, and a pin passing through said ear and the shank to secure the plate in place. 10

In testimony whereof I have hereunto affixed my signature.

ALEXANDER YESSAIAN.
